UNITED STATES PATENT OFFICE.

FRANK S. LIGGETT AND GEORGE J. E. MAYER, OF ALLEGHENY,
PENNSYLVANIA.

DESIGN FOR A CHECKER-BOARD.

SPECIFICATION forming part of Design No. 30,869, dated May 23, 1899.

Application filed April 3, 1899. Serial No. 711,609. Term of patent 7 years.

To all whom it may concern:

Be it known that we, FRANK S. LIGGETT and GEORGE J. E. MAYER, citizens of the United States of America, residing at Allegheny, in the county of Allegheny and State of Pennsylvania, have invented a certain new and useful Design for a Checker-Board, of which the following is a specification, reference being had therein to the accompanying drawing.

10 This invention relates to a certain new and ornamental design for checker-boards.

The design consists of a large square which is equally subdivided into sixty-four smaller squares, in which are arranged the following 15 figures: octagon, diamond, circle, smaller octagon figure, square, four-pointed star, an octagon having rounded corners, and a Maltese cross. The above-referred-to figures are arranged on the checker-board as herein 20 shown.

The drawing represents a plan view of our new design of checker-boards, in which the top row of figures is arranged in the following manner and is indicated by reference- 25 numerals: 1 represents an octagon; 2, a diamond; 3, a circle; 4, a smaller octagon figure; 5, a square; 6, a four-pointed star; 7, an octagon having rounded corners, and 8 a Maltese

cross, the second row of figures being exactly reverse, consisting of a Maltese cross 8, 30 arranged below the octagon 1; the octagon 7, having rounded corners, arranged below the diamond 2; the star 6, arranged below the circle 2; the square 5, arranged under the smaller octagon figure 4; the smaller octagon 35 figure 4, arranged under the square 5; the circle 3, arranged below the four-pointed star 6; the diamond 2, arranged below the octagon 7, having rounded corners, the larger octagon arranged under the Maltese cross. 40

The design is formed of alternate rows of figures, as described in the first and second rows.

Having thus described our invention, what we claim as new, and desire to secure by Letters Patent, is—

The design for a checker-board, as herein shown and described.

In testimony whereof we affix our signatures in the presence of two witnesses.

FRANK S. LIGGETT.
GEORGE J. E. MAYER.
